UNITED STATES PATENT OFFICE.

JAMES C. LAW, OF SCRANTON, PENNSYLVANIA.

APPARATUS FOR DISTRIBUTING GAS AND AIR IN FIRE BOXES.

Application filed February 6, 1926. Serial No. 86,551.

This invention relates to stoves and furnaces, and has for its object to provide for an improved distribution of air and gases within the fire box to promote the burning 5 of the fuel and to increase the heating effect. The invention is especially useful in connection with poor grade fuel.

The invention is embodied in an air and gas distributing device capable of being 10 mounted directly upon the grate of a stove or furnace without requiring any changes or alterations whatsoever in the furnace or in the grate thereof. The device is portable in the sense that it may be conveniently applied 15 and conveniently removed without disturbing any of the elements of the stove or furnace.

Provision is made for distributing pre-heated air and also gas drawn from the 20 burning body of the fuel over the top of the bed of fuel so as to combine with the gases rising from the top of the bed of fuel and producing a blue flame, thereby utilizing what is usually waste gases and products of 25 combustion. Provision is also made for regulating the discharge of air and gas across the top of the bed of fuel. The device is also mounted so that it may be rotated or oscillated on its vertical axis for 30 the purpose of breaking up clinkers which may form around the grate portion of the device.

With these and other objects in view, the present invention consists in the combination 35 and arrangement of parts as will be herein-after more fully described, illustrated in the accompanying drawings and particularly pointed out in the appended claims, it of course being understood that changes in the form, proportion, size and minor details 40 may be made, within the scope of the claims, without departing from the spirit or sacrificing any of the advantages of the invention.

In the drawing:

45 Figure 1 is a vertical sectional view of a fire-box ash-pit and grate of a conventional stove or furnace for domestic heating having the device of the present invention applied thereto.

50 Figure 2 is an enlarged sectional view on the line 2-2 of Figure 1.

Figure 3 is an enlarged sectional view on the line 3-3 of Figure 1.

55 For an understanding of the present invention I have shown in the accompanying drawing a furnace body 5 in which there is

a conventional or any preferred form of grate 6, dividing the furnace body into an ash-pit 7 and a fire-box 8. A fire or fuel door 9 is provided for the fire-box, and there 60 is the usual ash-pit door 10. As shown in the drawing the grate includes triangular grate bars which are mounted to rock on their longitudinal axes.

The air and gas distributor of the present 65 invention is in the general form of a tube 11, the lower portion 12 of which is laterally enlarged and slotted, as at 13, to form a grate section, as will hereinafter appear. The bottom of the device is open to admit 70 air upwardly into the tube, while the top 14 of the tube is closed and provided with an annular series of laterally directed openings or perforations 15 constituting jets for the 75 lateral discharge of preheated air and gas rising through the tube. These jets are controlled by a damper ring 16 rotatably embracing the perforated part of the tube and supported on an external annular shoulder or seat 17 on the tube. Perforations 18 are 80 provided in the damper ring for registration with the perforations in the tube for regulating the size of the jets to control the escape of air and gas through the jets. External shoulders or projections 19 are 85 provided on the damper ring for engagement by the tip of a poker thrust through the fire-door 9 whereby the damper may be adjusted. Across the top of the tube is a diametric 90 groove or seat 20 in which a poker may be placed and operated like a crank or lever to rotate the tube on its mounting on the grate; as will be hereinafter explained.

The distributor tube is seated in a base 95 member 21 in the form of a ring, surrounding the bottom of the tube, and having a base flange 22 which rests upon a pair of grate bars, and is provided with a pair of openings 23 to receive headed pins 24 which lie in the spaces between adjacent wings 25 of each 100 of the grate bars to prevent sidewise displacement of the base 21. Upon the grate portion 12 of the distributor tube there are several upright ribs 26 on the exterior of the tube, preferably adjacent certain of the slots 105 13. These ribs terminate short of the open bottom of the tube, and the bottom ends of the ribs constitute shoulders which rest upon the top of the base member. That portion of the distributor tube which lies within 110 the base member is circular in cross-section so as to provide for rotating or rock-

ing the tube on its longitudinal axis by manipulation of a poker placed sidewise in the seat 20 at the top of the tube. The pins 24 rest loosely in the openings in the base flange 22 and also loosely in the slots in the grate bars, whereby the latter may be rocked without disturbing the tube and the tube may be applied and removed with ease and dispatch.

At the juncture 27 of the grate portion 12 10 and the tube portion 11, there is an external flange portion 28, the top of which is inclined downwardly and outwardly from the tube, while the underside 29 of the flange is inclined or beveled upwardly and outwardly 15 from the tube.

In the use of my invention, the device is mounted in the manner shown and described, and fuel is introduced into the fire-box and upon the grate and the fire started in the 20 usual manner. As the fuel burns, a bed of ash 30 will accumulate upon the grate in the usual manner, and a bed of burning coals 31 will rest upon the top of the bed of ashes 30. It is the usual practice to maintain an ash 25 bed of about four inches in thickness. The slotted or grate portion of the distributor tube is of a length to extend slightly above the top of the ash bed, so that under natural draft, air will pass from the ash-pit upward- 30 ly through the open bottom of the distributor device, and will escape laterally outward through the slots 13 into the bed of burning coal so as to effectually supply air thereto and thereby promote combustion in the burn- 35 ing bed of coal. Air will also rise through the tube and will discharge through the registered openings 15 and 18 at the top of the tube so as to supply preheated air to mingle with the gases rising from the burn- 40 ing fuel and producing a blue flame extending across the top of the burning fuel thereby to produce heat and utilize what is normally waste product of combustion.

Sufficient air may be introduced into the 45 ash-pit without requiring the ash-pit door 10 being left open, by the provision of an inlet nipple 32 mounted in an opening 33 provided in a wall of the ash-pit.

The device may also be operated under 50 forced draft by the provision of an electric fan or blower 34 having its discharge nozzle 35 located adjacent to the flared open outer end of the nipple 32 and in axial alignment therewith. The lead 36 from the fan or 55 blower, may extend to any point and be connected with a suitable switch for starting and stopping the blower. Under forced draft, a considerable portion of the air introduced into the ash-pit will rise vertically 60 through the distributor device and will draw gases from the lower portion of the burning fuel 31 upwardly through the distributor device, and these gases and preheated air will mingle and discharge through the 65 jets 15 and produce a blue flame across the

top of the burning fuel, thereby utilizing what is normally waste products to increase the heating effect of the furnace. I have found that a fan or blower of very small capacity, for instance one delivering 25 to 70 35 cubic feet of air per minute and of 1/25 or 1/30 horse-power, is amply sufficient for domestic purposes. It is not necessary to employ the fan or blower continuously, and the purpose of the fan or blower is primarily 75 for use in the morning or at an other time for quickly promoting the combustion of the fuel and increasing the temperature of the furnace.

It is preferred to have the discharge nozzle of the fan or blower separate from but close to the open outer end of the air inlet of the ash-pit so that the fan may not become heated by conduction from the walls of the furnace. The inlet end of the nipple 80 32 is flared and of materially greater diameter than the discharge end of the blower nozzle 35 in order to supply a sufficient amount of air under natural draft and to provide for drawing in atmospheric air 85 through the inlet nipple other than that which is discharged from the discharge nozzle 35.

A very careful study of the present invention in operation has shown that the highly 90 preheated air passes from the distributor device into the combustion chamber, above the burning fuel, under natural draft, and immediately mixes with the carbon gases arising from the burning bed of fuel and is converted into carbonic acid gas CO_2 , and that under forced draft, the gases from the distillation portion of the burning fuel are drawn through the slotted portion of the distributor and unite with the oxygen of the 100 air passing upwardly through the device, and these united gases are ejected through the jets at the top of the device into the combustion chamber as carbonic acid gas CO_2 , 105 and the admixture of such gas with the carbon gases arising from the top of the coal bed produces a blue flame involving complete combustion of what would otherwise be waste products. It will therefore be understood that in addition to the physical device, 110 my invention involves a method of withdrawing gases from the distillation zone of the burning fuel, uniting them with preheated air drawn from the ash-pit, the conducting of the mixture upwardly through, but 115 out of contact with the burning fuel, and the discharging of the mixture across the top of the bed of fuel and into the carbon gases arising therefrom so as to bring about 120 a perfect combustion of these mixed gases, 125 all in a very simple and effective manner.

A further important feature of the invention, as shown by actual practice, where there is no spark or gas ignition present in the combustion chamber, as when charged with 130

fresh fuel, and whether under natural or forced draft, the nitrogen of the heated air, ascending through the distributor (about 79% by volume) and being lighter than air, 5 ascends and discharges rapidly, dilutes heavy volumes of explosive gas, and which diluted gas ascends more rapidly and passes off to the stack. In this respect the distributor or tube functions as a relief valve, the 10 principle being especially advantageous in burning bituminous coals, precluding the possibility of destructive gas explosions, without respect to the manner of "banking" the fuel.

15 What I claim is:

1. The combination with an ash-pit, a grate and a fire-box above the grate, of a gas and air distributor supported upon the grate and provided with a longitudinal passage communicating at its lower end with the ash-pit and having damper-controlled lateral discharge jets below and adjacent its upper end, the lower portion of the device having straight vertical side walls provided with 20 longitudinal slots of a length to extend above the normal ash-bed as and for the purpose described.

2. The combination with an ash-pit, a grate and a fire-box above the grate, of a gas and air distributor supported upon the grate and provided with a longitudinal passage communicating at its lower end with the ash-pit and having damper-controlled lateral discharge jets below and adjacent its upper 35 end, the lower portion of the device having straight vertical side walls provided with longitudinal slots of a length to extend above the normal ash-bed as and for the purpose described, said gas and air distributor being provided with external longitudinal clinker 40 breaking ribs on the slotted portion thereof, and said distributor being mounted for rotation on its longitudinal axis.

3. The combination with an ash-pit, a grate and a fire-box above the grate, of a circular seat mounted upon the grate, and a gas and air distributor rotatably mounted upon the seat, said distributor having a longitudinal passage communicating at its bottom 45 with the ash-pit and provided below and adjacent its upper end with damper-controlled laterally discharging jets, the lower portion of the distributor having straight vertical side walls provided with longitudinal slots rising above the normal height of the ash-bed as and for the purpose described, and also provided with external longitudinal ribs extending parallel with the slots and constituting clinker breaking elements.

4. The combination with an ash-pit, a grate and a fire-box above the grate, of a circular seat mounted upon the grate, and a gas and air distributor rotatably mounted upon the seat, said distributor having a longitudinal 50 passage communicating at its bottom

with the ash-pit and provided below and adjacent its upper end with laterally discharging jets, the lower portion of the distributor having straight vertical side walls provided with longitudinal slots rising above 70 the normal height of the ash-bed, and also provided with external longitudinal ribs extending parallel with the slots and constituting clinker breaking elements, the top of the distributor having a seat for the reception of a poker for the purpose of oscillating the distributor on its seat.

5. An air and gas distributor for fire-boxes, comprising a tubular distributor member provided near its top with laterally disposed damper-controlled exhaust jets and having its bottom end open, the lower portion of the device having vertical straight side walls provided with longitudinal slots having a length to extend above the top 75 of the ash-bed normally maintained upon a grate as and for the purpose described.

6. An air and gas distributor for fire-boxes, comprising a tubular distributor member provided near its top with laterally disposed damper controlled exhaust jets and having its bottom end open, the lower portion of the device having vertical straight side walls provided with longitudinal slots having a length to extend above the top of 80 the ash-bed normally maintained upon a grate as and for the purpose described, external longitudinal clinker breaking ribs upon the lower portion of the distributor member and extending parallel with the 85 slots, and a base to rest upon a grate and on which the distributor is rotatably mounted.

7. A gas and air distributor for fire-boxes, comprising a base having a vertical opening surrounded by an upstanding ring, a distributor tube having its lower portion rotatable within the ring of the base and provided with external longitudinal clinker breaking ribs resting at their bases on the ring, the bottom of the distributor being 90 open, the lower portion of the distributor having vertical straight side walls provided with longitudinal slots of a length to extend above the top of the ash-bed normally maintained on a grate as and for the purpose described, and the top of the distributor being closed and provided with damper controlled laterally discharging jets.

8. A gas and air distributor for fire-boxes, comprising a tubular distributing member open at its bottom end closed at its top end and provided with laterally discharging jets adjacent its top, a perforate damper ring rotatably embracing the jet portion of the distributor, the lower portion of the distributor having vertical straight side walls provided with longitudinal slots of a length as 100 and for the purpose described.

9. A gas and air distributor for fire-boxes, comprising a tubular distributing member 105

open at its bottom and closed at its top and provided with damper controlled laterally discharging jets below and adjacent its top, the lower portion of the distributor having vertical straight side walls provided with longitudinal slots of a length to extend above the top of the ash-bed normally maintained upon a grate as and for the purpose described, there being an external annular flange overhanging the tops of the slots, the underside of the flange being inclined upwardly and outwardly.

JAMES C. LAW.
